Primary Examiner — Patricia Palasik(74) *Attorney, Agent, or Firm* — Nixon & Vanderhye P.C.(57) **CLAIM**

The ornamental design for a carrier bar, as shown and described.

DESCRIPTION

FIG. 1 is an enlarged partial perspective view, from the top, of a carrier bar according to our new ornamental design; FIG. 2 is a top view thereof;

FIG. 3 is a front view thereof, with the rear view being identical thereto;

FIG. 4 is an enlarged cross section taken along lines 4-4 of FIG. 2; and,

FIG. 5 is an enlarged cross section taken along lines 5-5 of FIG. 2.

The dotted lines represent the border between claimed and non-claimed subject matter and form no part of the claimed design.

The dashed lines represent environmental structure only and do not form a part of the claimed design.
